UNITED STATES PATENT OFFICE.

JOSEPH P. CLARKE, OF SAN FRANCISCO, CALIFORNIA.

DENTAL UNIT.

Application filed March 25, 1926. Serial No. 97,163.

The present invention relates to improvements in dental units, and more particularly to improvements in the cuspidor bowls borne thereby or mounted in conjunction therewith.

Customarily, the practice heretofore has been to mount the cuspidor in divers ways relative to the unit, but invariably with the water connections arranged exteriorly of the cuspidor and, in many instances, independently of the pedestal.

My invention has for its primary object the provision of a cuspidor of the character specified bearing self-contained flushing ducts of such disposition and arrangement as to produce a swirling motion in the water upon entering the bowl for the more thorough flushing and cleansing of the interior bowl surface.

A further object of the present invention is the provision of a dental cuspidor adapted to fit any standard unit and embodying within its own construction and as an integral part thereof novel flushing means, and of a design adapted to be used independently, or, where desired, in connection with its own standard or support.

An additional object of the invention is the provision of a dental unit of neat and attractive design having as a supporting standard a hollow pedestal bearing exteriorly the various appurtenances necessary to the dentist in treatment of patients, and housing interiorly the valve-controlled connections serving to unite certain of these appurtenances to water, air, gas, electric, or such other supply source as may be necessary to their proper utilization.

Additional to the foregoing is the provision, in connection with a dental cuspidor of the character designated, of flexible tubular members connecting with the water supply line, one above and the other below the valve in this line and adapted respectively for excess secretions removal from the patient's mouth while under treatment and for mouth rinsing, the latter being supplied with a conveniently arranged push-button actuated valve.

Another object is the provision of a cuspidor bowl of the character designated that is provided with novel means for securing the bowl to the pedestal.

In the accompanying drawings, forming a part of this specification and in which similar characters of reference refer to like parts, 55 throughout:

Figure 1 is a perspective view of a dental unit of the "Ritter" type, showing an embodiment of my invention as substituted for the ordinary cuspidor bowl, used in connection with this type of unit.

Figure 2 is a perspective view of a pedestal and cuspidor bowl, showing an embodiment of one type of cuspidor bowl and its connections constructed in accordance with 65 my invention;

Figure 3 is a plan view of the cuspidor bowl, with parts broken away for the better illustration of the relative positions of the flushing duct discharge openings; 70

Figure 4 is a side view partly in section, showing an embodiment of my improved cuspidor bowl as applied to a pedestal and independent of the unit, the water connections to the rinsing nozzle and the flexible 75 connection to the saliva tube being shown in their respective positions;

Figure 5 is a detail view of a sanitary nozzle borne by a flexible tube and adapted for the convenience of the patient in mouth rinsing; and 80

Figure 6 is a plan view of the nozzle shown in Figure 5.

Referring more particularly to the drawings, in which a preferred embodiment of 85 my invention is illustrated in Figures 2, 3 and 4, 1 represents a hollow cast pedestal having a frusto conical head 2 at its upper end provided with a flat top 3 and screw threaded exterior upper edge 4, said flat 90 top providing a cuspidor bowl seat, upon which the cuspidor is mounted and held rigidly in position.

The top 3 of the pedestal head has a centrally positioned base 5 forming a drain outlet into which a drain pipe 6 is tapped. The cuspidor bowl 7 is preferably constructed of either porcelain or glass and is open at its upper end 8 and provided with an integral flange 9 surrounding its inner edge, the lower end 100 thereof forming a flat base and exteriorly formed bead of slightly less diameter than the upper end of the head 2 of the pedestal and provided interiorly with a central dis-

charge opening 10 communicating with the drain pipe 6, said bowl having its base 11 seated upon a protective gasket 12 resting upon the flat top 3 of the pedestal head and 5 having said gasket extending up around the edge of the bead, to protect the bowl from contact with the metal pedestal.

The means for clamping the bowl 7 to the pedestal head 2 consists of a union nut 13 10 having an internal flange 14 adapted to rest upon the bead of the bowl neck and provided with internal threads adapted to fit the external threads 4 formed upon the said head 2 of the pedestal. The bowl is drawn 15 down tightly upon the gasket 12, through this means without injury and will thereby form water tight contact between the bowl and its water inlet and discharge connections.

The bowl is provided with inlet ducts 15 20 and 16 formed in opposite sides of its wall and extending upwardly in substantially spiral manner and opening directly thereinto, with their lower ends communicating with an annular port 17 formed in the base 25 and surrounding the discharge 10, their upper ends 18 and 19 being located just beneath the flange 9 and adapted to discharge against the interior bowl surface and to give a swirling motion to the entering 30 water. The annular port 17 is supplied with water through an inlet pipe 20 tapped into the member 3, the flow being controlled by a valve 21 having its stem projecting through the pedestal wall just below the 35 bowl and provided with a wheel for its manipulation.

The rinsing nozzle 22 is adapted to normally rest against the head 2 of the pedestal just below the bowl and conveniently within 40 reach of the patient, the nozzle being borne by a flexible tube 24 the opposite extremity of which extends through an opening 25 in the pedestal head and connects with the inlet pipe 20, the nozzle flow being 45 controlled by a push-button 26 and held over the basin, or bowl, by the patient while rinsing the mouth. If desired a thermal unit 50 may be enclosed within the tube 24 adjacent the nozzle 22 for the purpose of raising the temperature of the water in its passage therethrough.

In Figure 1, the bowl 27 is shown mounted upon a support 28 of a typical dental unit 55 29, the bowl in this design being connected to the water supply in the main supply by a nipple 30, the flow of water being controllable through a valve 31 connected to the supply line, not shown. The rinsing connection 32 may be brought through an 60 opening in the standard and a nozzle 33 similar to the nozzle 22 secured to its outer end and held in place by an opening 34 formed in the standard 29.

The saliva tube 35, of suction character 65 and similar to those generally employed in

connection with dental units and of ejector principle, is shown in Figure 4 as connected to the inlet pipe 20 above the valve 21 by a pipe connection 36, the mouth-piece 37 being connected to the free end of the tube 35 70 and secured conveniently at hand in readiness for use, its operation being dependent upon the lowered pressure induced in the tube by the rapid flow of water in pipe 20 past the tube mouth as it is being discharged 75 into the bowl.

Having thus described my invention, I claim, and desire to secure by Letters Patent:

1. In a dental unit, in combination, a cuspidor-supporting pedestal having a frusto-conical head bearing screw-threads at its upper end, a cuspidor borne by said pedestal and consisting of a hollow bowl bearing a base having an annular bead formed at its edge, an interiorly flanged upper edge and a central discharge opening, a nut loosely borne by said beaded base and adapted to engage said screw-threaded pedestal head, said bowl having a self-contained duct 80 formed within its base and surrounding said discharge opening, a plurality of similar ducts communicating therewith and extending therefrom spirally and upwardly within the wall of said bowl and opening into the 85 interior thereof at opposite points, and a water-supply pipe enclosed within said pedestal and communicating with said ducts.

2. In a dental unit, in combination, a cuspidor-supporting pedestal having a frusto-conical head bearing external screw-threads at its upper end, a cuspidor consisting of a hollow bowl having a solid base and beaded lower edge adapted to seat upon said pedestal head, a nut loosely borne by 100 said beaded base and adapted to engage said screw-threaded pedestal head, a gasket between said pedestal head and said bowl base, said bowl having a self-contained duct formed within its base and surrounding a 105 discharge opening, a plurality of similar ducts communicating therewith and extending therefrom spirally and upwardly within the wall of said bowl and opening into the interior thereof at opposite points, and a 110 valve-controlled water-supply pipe enclosed within said pedestal and communicating with the said ducts.

3. In a dental unit, in combination, a pedestal having a frusto-conical head bearing a smaller base forming a cuspidor support and having external screw-threads at its upper end, a cuspidor consisting of a hollow bowl having a solid base of a diameter equalling that of the smaller base of 120 said pedestal and adapted to seat thereon, an annular bead formed at the lower edge of said bowl base, a nut loosely borne by said bead and adapted to engage the screw-threads formed on said pedestal head, a 125

gasket resting upon said pedestal head and forming a water-tight joint between the head and bowl, a discharge opening formed in the base of said bowl, a duct surrounding said discharge opening, a plurality of ducts communicating therewith and extending therefrom upwardly within the wall of said

bowl and opening into the interior thereof at opposite points, and a valve-controlled water-supply pipe enclosed within said pedestal and communicating with said ducts. ⁴⁰

In testimony whereof I have affixed my signature.

JOSEPH P. CLARKE.
